UNITED STATES PATENT OFFICE.

JUNIUS M. DAVISSON, OF BIRMINGHAM, ALABAMA.

CUP COVER.

Application filed June 18, 1923. Serial No. 848,232.

To all whom it may concern:

Be it known that I, JUNIUS M. DAVISSON, a citizen of the United States, residing at Birmingham, in the county of Jefferson and State of Alabama, have invented a new and useful Cup Cover, of which the following is a specification.

This invention relates to a cover designed primarily for use on coffee cups and the like in 10 cafeterias and other places wherein it is necessary to convey filled cups and other receptacles from place to place. It is well known that it is a difficult matter to carry a filled cup on a tray without spilling the 15 contents thereof. One of the objects of the present invention is to provide a simple and inexpensive cover that can be placed readily on the cup or other similar container so as to prevent the contents of the cup from 20 splashing and also to protect the contents against dust, insects, etc.

A further object is to provide a cover of this character which will be held in place by friction, it being intended to throw away 25 the cover after it has been used.

With the foregoing and other objects in view which will appear as the description proceeds, the invention resides in the combination and arrangement of parts and in the 30 details of construction hereinafter described and claimed, it being understood that changes in the precise embodiment of the invention herein disclosed, may be made within the scope of what is claimed without departing 35 from the spirit of the invention.

In the accompanying drawing the preferred form of the invention has been shown.

In said drawings

Figure 1 is a plan view of the cover.

Fig. 2 is a section on line 2—2, Fig. 1, a portion of a cup being shown by broken lines.

Referring to the figures by characters of reference 1 designates a disk of paraffined paper or other suitable material, the marginal portion of which is curled inwardly as indicated at 2 to provide a resilient gripping jaw or bead. Secured to the bottom of this disk is a ring 3 one edge of which is 50 curled outwardly as shown at 4 to provide a

resilient jaw or bead, the two jaws 2 and 4 cooperating to form an annular or circular channel 5. The width of this channel is such that when a cover is placed on a cup or other container of one size the jaw will frictionally engage the outer surface thereof. However when the cover is placed on a small sized container, the jaw 4 will press outwardly against the inner surface of the container. Thus, it will be obvious that the 55 jaws can be placed under more or less pressure to adapt the cover for use in connection with different sizes of cups, etc. It is not necessary to make a cover for every size of cup used. Instead a cover of one size 60 can be used with cups of several sizes. This has been found to be a feature of considerable importance, in cafeterias, lunch rooms, and other places where cups, glasses and the like of various sizes are used. 65

What is claimed is:—

1. A cover for frictional engagement with the inner or outer surfaces of containers of different diameters comprising a paper disk and concentric paper jaws upon one face of 70 the disk and spaced apart to provide an annular container receiving channel, the said jaws having portions converging toward the disk, the said portions being yieldable for frictional engagement with different containers within predetermined size limits. 75

2. A cover for containers of different sizes including a paper disk and concentric jaws on one face of the disk, each jaw comprising a curled or rolled paper portion having 80 its free edge extended toward the disk, said jaws converging upwardly toward the disk and the free edge portions being shiftable to vary the width of the channel between the jaws, thereby to receive within the channel 85 containers of different diameters and to frictionally engage the same.

In testimony that I claim the foregoing as my own, I have hereto affixed my signature in the presence of two witnesses.

JUNIUS M. DAVISSON.

Witnesses:

Y. A. DYER,

Mrs. ANNA H. DYER.
